ABSTRACT OF THE DISCLOSURE

The compounds are 11-aminoalkylenemorphanthridines which are useful as central nervous system depressants, skeletal muscle relaxants and antitremor agents. Representative of the compounds disclosed are 11-(3-dimethylaminopropylidene)morphanthridine and 2-chloro-11-(3-dimethylaminopropylidene)morphanthridine.

DESCRIPTION OF THE INVENTION

The compounds of the present invention may be represented by the following formula:

in which X and Y are members of the group consisting of 30 hydrogen, halogen such as chloro, bromo and fluoro, lower alkoxy such as methoxy and ethoxy, lower alkyl of 1 to 4 carbon atoms such as methyl and ethyl, thio-lower alkyl such as thiomethyl and thioethyl and trifluoromethyl, R₁ is hydrogen or a lower alkyl of 1 to 4 carbon atoms such as methyl, ethyl or propyl, n is a number from 0 to 4 and Am is selected from (a)

in which R₂ and R₃ are selected from hydrogen, lower alkyl of 1 to 4 carbon atoms such as methyl, ethyl or isopropyl, a phenyl-lower alkyl of 7 to 13 carbon atoms such as benzyl, phenethyl or phenylisopropyl, a cycloalkyl of 3 to 7 carbon atoms such as cyclopropyl, cyclopentyl and cyclohexyl and cycloalkyl-lower alkyl groups in which the cycloalkyl group contains 3 to 7 carbon atoms such as cyclopentyl-ethyl and cyclohexyl-methyl or

(b) a heterocyclic amino group such as morpholino, pyrrolidino, piperidino, N-lower alkyl piperazino such as N-methylpiperazino, N-phenyl-lower alkyl piperazino groups such as N-benzyl piperazino and N-(hydroxy-lower alkyl)-piperazino groups such as 4-(β-hydroxyethyl) piperazino.

The compounds of the present invention may be conveniently prepared from the corresponding substituted 11-morphanthridones which have the following formula:

in which X and Y are as previously defined. These compounds are known compounds and may be prepared as described by R. G. Cooke and I. M. Russell. *Tetrahedron Letters*, 1968 (44), 4587-8.

2

Representative of the compounds that may be employed are:

- 5 11-morphanthridone,
- 2-chloro-11-morphanthridone,
- 2-fluoro-11-morphanthridone,
- 3-chloro-11-morphanthridone,
- 2-trifluoromethyl-11-morphanthridone,
- 2-methoxy-11-morphanthridone,
- 2-thiomethyl-11-morphanthridone,
- 10 2-methyl-11-morphanthridone,
- 8-methyl-11-morphanthridone, and
- 9-methyl-11-morphanthridone.

In the preferred practice of the present invention the compounds are prepared by the reaction of the 11-morphanthridone and an aminoalkylphosphonium compound and a strong base such as butyl lithium. The reaction is preferably carried out in a mutual solvent, such as tetrahydrofuran, at reflux. The reaction is generally complete in about 10 hours and the desired morphanthridine derivative isolated by conventional techniques.

The described process may be illustrated as follows:

in which R is an alkyl group of 1 to 4 carbon atoms, phenyl, aminophenyl or benzyl, and R₁, n and Am are as defined previously.

The aminoalkylphosphonium compounds may be prepared as described in U.S. Pat. No. 3,354,155. Representative of such compounds which may be employed are the following:

- 3-dimethylaminopropyltriphenylphosphonium bromide hydrobromide,
- 3-(1-piperazinopropyl)triphenylphosphonium bromide hydrobromide,
- 3-(4-hydroxyethyl-1-piperazinopropyl)triphenylphosphonium bromide hydrobromide,
- 55 3-diethylaminopropyltriphenylphosphonium bromide hydrobromide, and
- 3-methylaminopropyltriphenylphosphonium bromide hydrobromide.

Representative of the compounds which may be prepared by the described process are the following:

- 11-(3-dimethylaminopropylidene)morphanthridine,
- 2-chloro-11-(3-dimethylaminopropylidene)morphanthridine,
- 65 2-trifluoromethyl-11-(3-dimethylaminopropylidene)morphanthridine,
- 11-(3-piperazinopropylidene)morphanthridine,
- 2-chloro-11-(3-piperazinopropylidene)morphanthridine,
- 2-trifluoromethyl-11-(3-piperazinopropylidene)morphanthridine,
- 70 11-[3-(4-hydroxyethyl)piperazinopropylidene]morphanthridine,

3

2-chloro-11-[3-(4-hydroxyethylpiperazinopropylidene)] morphanthridine,
 2-trifluoromethyl-11-[3-(4-hydroxyethylpiperazinopropylidene)] morphanthridine,
 11-(3-diethylaminopropylidene) morphanthridine,
 2-chloro-11-(3-diethylaminopropylidene) morphanthridine,
 2-trifluoromethyl-11-(3-diethylaminopropylidene) morphanthridine,
 11-(3-methylaminopropylidene) morphanthridine,
 2-chloro-11-(3-methylaminopropylidene) morphanthridine, and
 2-trifluoromethyl-11-(3-methylaminopropylidene) morphanthridine.

The final compounds exist as both the cis and trans isomers which are separable.

The compounds of the present invention have been found to possess utility as pharmaceutical agents, especially central nervous system depressants and agents for treating Parkinson's disease and drug induced extra pyramidal disorders. In mouse behavioral studies the compounds 11-(3-dimethylaminopropylidene) morphanthridine and 2-chloro-11-(3-dimethylaminopropylidene) morphanthridine were found in doses of 10 mg./kg. intraperitoneally to cause central nervous system depression. The studies also indicated that the compounds had LD₅₀'s in excess of 150 mg./kg. intraperitoneally.

Each of the aforementioned compounds were also tested for antitremor activity. In the tests the compounds were administered to mice in doses of 0.3 to 30 mg./kg. intraperitoneally prior to challenge with oxotremorine. Oxotremorine, when administered to normal nonmedicated animals produces a tremor, rigidity, and parasympathomimetic stimulation which very closely resembles the rigidity and tremor of Parkinson's disease. The similarity of oxotremorine induced behavior in animals to that seen in Parkinson's disease in man, coupled with the fact that all agents found to be useful in treating Parkinson's disease also blocked the effects of oxotremorine in animals, has lead to the general use of oxotremorine in the screening of drugs for anti-Parkinsonism activity. Animals pretreated with 8 mg./kg. of the above mentioned compounds were completely protected from the effects of oxotremorine challenge. The test indicated that the compounds had an antitremor ED₅₀ of about 4 mg./kg. intraperitoneally. Significantly the blockade of the oxotremorine effects was accomplished at dose levels which produced very little in the way of undesirable side effects such as mydriasis.

When employed as pharmaceutical agents the compounds are preferably used in the form of acid addition salts. Such acid addition salts may be conveniently prepared by conventional means such as by contacting the compounds with a suitable acid in a mutual solvent and then removing the solvent to obtain the desired salt. Examples of acids which may be used are hydrochloric acid, succinic acid, tartaric acid, benzoic acid or fumaric acid.

Quaternary ammonium salts of the compounds may be formed by conventional techniques employing a suitable alkylating agent such as methyl chloride, methyl iodide or ethyl bromide.

Pharmaceutical dosage forms containing the active ingredients are generally prepared by combining the active ingredients or ingredients with a major amount of one or more suitable pharmaceutical diluents and then forming the resulting mixture into unit dosage forms suitable for oral or parenteral administration.

The unit dosage forms will generally contain from 5 to 250 mg. of the active ingredients. One or more of such units may be administered daily depending upon the patient's physical size and the severity of the condition being treated. However, generally the daily dosage will not exceed 150 mg. of the active ingredient per kilogram of the patient's body weight.

4

Representative of a suitable pharmaceutical composition which may be prepared are the following:

TABLETS

		G.
5	11 - (3 - dimethylaminopropylidene) morphanthridine	25
	Methyl cellulose, 400 cps.	4
	Lactose	9
10	Magnesium stearate	0.4
	Starch	1.6

The powders, other than magnesium stearate, are granulated with water, passed through a No. 16 mesh screen and dried at 50° C. Magnesium stearate is mixed in and 40 mg. tablets are pressed.

The practice of the invention is further illustrated by the following examples:

EXAMPLE 1

11-(3-dimethylaminopropylidene) morphanthridine

To a cooled slurry of 16.4 g. (0.032 mole) of 3-dimethylaminopropyltriphenylphosphonium bromide hydrobromide in 50 ml. of tetrahydrofuran is added with stirring 0.064 mole of butyl lithium solution. The mixture is stirred 1 hour at room temperature, cooled, and 4.97 (0.029 mole of 11 - morphanthridone in 25 ml. of tetrahydrofuran added dropwise. The solution is stirred for 1.5 hours at room temperature, refluxed for 10 hours, cooled, 20 ml. of water added and the mixture concentrated. The residue is treated with dilute aqueous hydrochloric acid and benzene, and the aqueous layer separated and made alkaline with potassium hydroxide. The resulting oil is extracted into ether, dried over potassium carbonate, filtered, concentrated, and distilled to yield 11-(3-dimethylaminopropylidene) morphanthridine, B.P. 188-200° (0.05 mm.). This base is then converted to the bis-cyclohexylsulfamate, M.P. 116-117°.

Analysis.—Calcd. for C₃₁H₄₆N₄O₆S₂ (percent): C, 58.64; H, 7.30; N, 8.82. Found (percent): C, 58.90; H, 7.55; N, 8.82.

EXAMPLE 2

2-chloro-11-(3-dimethylaminopropylidene) morphanthridine

To a cooled slurry of 5.1 g. (0.01 mole) of 3-dimethylaminopropyltriphenylphosphonium bromide hydrobromide in 20 ml. of tetrahydrofuran is added with stirring 0.02 mole of butyl lithium solution. The mixture is stirred 1 hour at room temperature, cooled, and 1.9 g. (0.0079 mole) of 2 - chloro - 11-morphanthridone (M.P. 130.5°) in 20 ml. of tetrahydrofuran added dropwise. The solution is stirred for 1.5 hours at room temperature, refluxed for 11 hours, cooled, 7 ml. of water added, and the mixture is then concentrated. The residue is treated with dilute cold hydrochloric acid and benzene, the aqueous layer separated, made alkaline with potassium hydroxide, and extracted with ether. The ethereal extracts are dried over potassium carbonate, filtered, and concentrated and the residue distilled to yield 2 - chloro - 11 - (3-dimethylaminopropylidene) morphanthridine as a viscous oil, B.P. 180-200° (0.05 mm.). This oil is chromatographed over silica gel using benzene-methanol (ratio 4:1) as eluent. Fractions totaling 0.77 g. were collected and redistilled to afford 2 - chloro - 11 - (3 - dimethylaminopropylidene) morphanthridine as a yellow viscous base.

Analysis.—Calcd. for C₁₉H₂₀ClN₂ (percent): C, 73.18; H, 6.46; N, 8.99. Found (percent): C, 73.30; H, 6.62; N, 8.90.

EXAMPLE 3

The process of Example 1 may be repeated using in place of 3 - dimethylaminopropyltriphenylphosphonium bromide hydrobromide one of the following:

3-(1-piperazinopropyl)triphenylphosphonium bromide hydrobromide,

3-(4-hydroxyethyl-1-piperazinopropyl)triphenylphosphonium bromide hydrobromide, 3-diethylaminopropyltriphenylphosphonium bromide hydrobromide, and 3-methylaminopropyltriphenylphosphonium bromide hydrobromide, respectively

to obtain

11-(3-piperazinopropylidene)morphanthridine, 11-[3-(4-hydroxyethylpiperazinopropylidene)] morphanthridine, 11-(3-diethylaminopropylidene)morphanthridine, and 11-(3-methylaminopropylidene)morphanthridine, respectively.

EXAMPLE 4

The process of Example 2 may be repeated using in place of 3 - dimethylaminopropyltriphenylphosphonium bromide hydrobromide one of the following:

3-(1-piperazinopropyl)triphenylphosphonium bromide hydrobromide, 3-(4-hydroxyethyl-1-piperazinopropyl)triphenylphosphonium bromide hydrobromide, 3-diethylaminopropyltriphenylphosphonium bromide hydrobromide, and 3-methylaminopropyltriphenylphosphonium bromide hydrobromide, respectively

to obtain

2-chloro-11-(3-piperazinopropylidene)morphanthridine, 2-chloro-11-[3-(4-hydroxyethylpiperazinopropylidene)] morphanthridine, 2-chloro-11-(3-diethylaminopropylidene)morphanthridine, and 2-chloro-11-(3-methylaminopropylidene)morphanthridine, respectively.

I claim:

1. A compound selected from compounds and acid addition salts of compounds of the formula

in which X and Y are members of the group consisting of hydrogen, halogen, lower alkoxy, lower alkyl, thio-lower alkyl and trifluoromethyl, R₁ is hydrogen or lower alkyl, n is 0 to 4 and Am is selected from

(a)

in which R₂ and R₃ are selected from hydrogen, lower alkyl, phenyl-lower alkyl of 7 to 13 carbon atoms, cycloalkyl of 3 to 7 carbon atoms and cy-

cloalkyl-lower alkyl in which the cycloalkyl contains 3 to 7 carbon atoms, or

(b) a heterocyclic amino group selected from morpholino, pyrrolidino, piperidino, N-lower alkyl piperazino, N-phenyl-lower alkyl piperazino and N-(hydroxy-lower alkyl)-piperazino.

2. A compound of claim 1 in which Am is

3. A compound of claim 1 in which Am is a heterocyclic amino group selected from morpholino, pyrrolidino, N-lower alkyl piperazino, N-phenyl-lower alkyl piperazino and N-hydroxy-lower alkyl-piperazino.

4. A compound of claim 1 in which X and Y are hydrogen, halogen or trifluoromethyl.

5. A compound of claim 1 in which R₁ is hydrogen or methyl.

6. A compound of claim 1 in which X and Y are hydrogen or chloro, R₁ is hydrogen and Am is

in which R₂ and R₃ are methyl.

7. A compound of claim 1 in which X is hydrogen, Y is chloro, R₁ is hydrogen and Am is

in which R₂ and R₃ are methyl.

8. A compound of the formula

wherein R₁ and R₂ are hydrogen or chlorine.

9. 11-(3-dimethylaminopropylidene)morphanthridine.

10. 2-chloro-11-(3-dimethylaminopropylidene)morphanthridine.
